UNITED STATES PATENT OFFICE.

CHARLES A. HYDE, OF ST. DAVIDS, PENNSYLVANIA.

DESIGN FOR A GARMENT-HANGER.

SPECIFICATION forming part of Design No. 34,225, dated March 12, 1901.

Application filed January 17, 1901. Serial No. 43,668. Term of patent 7 years.

To all whom it may concern:

Be it known that I, CHARLES A. HYDE, a citizen of the United States, residing at St. Davids, in the county of Delaware, State of Pennsylvania, have invented and produced a new and original Design for Garment-Hangers, of which the following is a specification, reference being had to the accompanying drawings, forming part thereof.

- 10 The leading feature of my design for a garment-hanger is a garment-hanger composed of a neck and arms projecting laterally therefrom and having the front face of said neck form an unbroken continuity from the inner end of one of the front walls of said arms to the inner end of the front wall of the opposite arm, the rear face of said neck being convex and the top of said neck receding from front to rear.
- 15 Figure 1 represents a rear elevation of a garment-hanger embodying my invention.

Fig. 2 represents a plan view thereof. Fig. 3 represents a vertical section on line $x\ x$, Fig. 1. Fig. 4 represents a vertical section on line $y\ y$, Fig. 1. 25

In the drawings, A designates a garment-hanger, the same being formed of the arms B and the neck C, the latter rising from the place of junction of said arms. The neck C has its rear face D convex and its top E receding from front to rear. The arms B are of channeled or skeleton form in transverse direction. 30

Having thus described my invention, what I claim as new, and desire to secure by Letters 35 Patent, is—

The design for a garment-hanger substantially as shown and described.

CHARLES A. HYDE.
